THREAD BOARD AND GUIDE FOR SPINNING FRAMES

Application filed July 27, 1928. Serial No. 295,807.

This invention relates to a thread board and guide for a spinning frame, the invention relating more particularly to frames for spinning wool.

It is one object of our invention to provide a thread board and guide adapted to resist the excessive wear caused by the friction of wool yarn.

A further object is to provide a construction of thread board and guide which will prevent accidental unthreading when yarn having either a right hand or a left hand twist is used.

Our invention further relates to the provision of a construction in which the yarn guide may be conveniently adjusted relative to the thread board and by which said guide may be effectively held in operative position.

A preferred form of our invention is shown in the drawings in which

Fig. 1 is a plan view of parts of a thread board embodying our improvements;

Fig. 2 is a side elevation, looking in the direction of the arrow 2 in Fig. 1;

Fig. 3 is a sectional front elevation of one of the thread board members, taken along the line 3—3 in Fig. 1;

Fig. 4 is a similar view, taken along the line 4—4 in Fig. 1;

Fig. 5 is a perspective view of a porcelain thread guide, and

Fig. 6 is a perspective view of a holder therefor.

Referring to the drawings, we have shown a portion of a spinning frame 10 to which a thread board rail or support 11 is bolted. We have also indicated the position of drawing rolls 12 and 13 and a ring rail 14 supporting the usual spinning rings 15 and travelers 16 by which the yarn Y is wound on the bobbins B, all of these parts being of the usual construction.

A plurality of thread board members 20 are hinged at 21 on the rail or support 11 and are supported in substantially horizontal position thereby. The members 20 may be swung back to the dotted line position in Fig. 2, as is usual when doffing the spindles.

Blocks 24 are secured to the hinges 21, as by screws 25 and the thread board members

20 are secured to the blocks 24 by bolts 28 (Fig. 3).

A porcelain thread guide 30 is provided for each member 20, each guide having a central opening 31 and an inclined threading slot 32 in its front or outer face. The guide 30 is retained in a holder 35 (Fig. 6) having a recess 36 in which the yarn guide is seated and retained.

The holder 35 also has a shank portion 37, 60 adapted to extend into a slot or recess 38 in the upper face of one of the blocks 24. The recess 38, however, is of slightly less thickness than the block 37, and is also of slightly greater width.

The holder 35 is freely adjustable forward and rearward to centrally align the opening 31 over the axis of the bobbin B, and the yarn guide may also be slightly adjusted sidewise by swinging the holder in the slot 38, such 70 width of the slot.

When the bolts 28 are tightened, the thread board member or plate 20 is drawn against the shank 37, and the holder 35 is firmly secured thereby.

The thread board member 20 is preferably formed of sheet steel and has a central opening 40 (Fig. 1) and a threading slot 41 extending inward from the front or outer edge 80 of the plate. The slot 40 is inclined to the left, as viewed in Fig. 1, providing a hook-like projection 42, which is preferably bent upward out of the plane of the member 20, as indicated in Figs. 2 and 4.

With the construction shown, it is found that the thread board and yarn guide are conveniently threaded by passing the thread to the left around the hook 42 and then to the right into alignment with the slot 32, by which the thread is admitted to the central passage 31 of the porcelain yarn guide. It is found also that the thread cannot be readily displaced from the yarn guide and thread board member during the operation of the machine, whether the thread is right hand twist or left hand twist, and in this respect our invention is a very substantial improvement over the previously used constructions 100

which were very likely to unthread when the direction of twist was reversed.

Having thus described our invention and the advantages thereof we do not wish to be limited to the details herein disclosed otherwise than as set forth in the claims, but what we do claim is:—

1. In a spinning frame, a thread board having a yarn threading and guiding opening therein, a yarn guide centered under said opening, said yarn guide having an inclined threading slot at the front thereof, and said thread board having an upwardly displaced hook overlying said slot.
- 10 2. In a spinning frame, a thread board having a threading and yarn guiding opening therein, a yarn guide centered under said opening, said yarn guide having a threading slot in its front face inclined upwardly and to the right, and said thread board having a hook portion overlying said threading slot and inclined upwardly and to the left.
- 15 3. In a spinning frame, a thread board having a yarn threading and guiding opening therein, a yarn guide centered under said opening, said yarn guide having a threading slot in its front face inclined upwardly in one direction and said thread board having a hook portion overlying said threading slot and inclined upwardly in the opposite direction.
- 20 4. In a spinning frame, a thread board having a yarn threading and guiding opening inclined in one direction, a yarn guide centered under said opening, and a holder for said yarn guide secured under said thread board and adjustable forward and rearward relative thereto, said yarn guide having a threading slot in its front face inclined in a direction opposite to that of the guiding opening.

In testimony whereof we have hereunto affixed our signatures.

FRED K. HENDRICKSON.
